TREATMENT OF NAPHTHENE BASE OIL

Charles T. Anné, Herman I. Wilson, and William C. Patterson, Port Arthur, Tex., assignors to The Texas Company, New York, N. Y., a corporation of Delaware

Application August 25, 1938, Serial No. 226,630

11 Claims. (Cl. 196—34)

This invention relates to the treatment of naphthene base oil. It particularly concerns the treatment of lubricating oil stocks derived from naphthene base crude petroleum for the production of lubricating oils substantially free from asphaltic and organic acidic constituents but having a desirable green cast or bloom.

The invention broadly contemplates treatment of fractions derived from naphthene base crude by a process involving deasphalting in the presence of a liquefied normally gaseous petroleum hydrocarbon solvent and treatment of these fractions with alkali in the presence of the liquefied solvent for the purpose of separating therefrom the naturally occurring organic acid constituents.

The process of this invention is particularly adapted to the preparation of lubricating oil having a desirable green cast and substantially free from asphaltic and acidic constituents from lubricating oil stocks derived from naphthene base crudes and particularly the residual fractions of such crudes.

The process is also applicable to the treatment of heavy residual fractions of naphthene base crudes rich in naphthenic acids such as the still bottoms produced in the vacuum distillation over caustic of lubricating oil fractions derived from Gulf Coastal crude. These bottoms are treated with acid in order to liberate a fraction comprising crude naphthenic acids. This crude fraction is treated with propane to precipitate asphaltic and tarry matter. Following this, the naphthenic acid material, while still diluted with propane, is treated with an alkali to saponify the acids and the resulting saponified material is then separated from the oily constituents. The saponified acids may be subsequently treated with an inorganic acid in order to liberate them.

It has been found that lubricating oils of desirable green cast can be prepared by deasphalting naphthene base reduced crude and treating the oil, while in propane solution, with an aqueous solution of caustic soda for the removal of naphthenic acids.

In the conventional treatment of this type of reduced crude this green cast is destroyed and oil having a blue cast or bloom results.

The conventional treatment of these lubricating oil fractions has usually involved treatment with an inorganic acid, followed by neutralization. Vacuum distillation over caustic has also been employed, or a combination such as chemical treatment and vacuum distillation.

55 Acid treatment apparently removes, along with

the undesired asphaltic and tarry bodies, all, or substantially all, of those constituents present in the oil and which impart to the oil a desirable green cast. Vacuum distillation over caustic also destroys this green cast. The purpose of distilling over caustic is to remove the naphthenic acids in the form of a soap which remains behind in the still as a residue. The desirable green color-forming constituents apparently remain in this residue and consequently are not present in the 10 distillate lubricating oil fractions.

From a practical standpoint it is impossible to effect removal of the naphthenic acids from the oil by simply washing with caustic soda solution, due to the extreme readiness with which emulsions are formed and the extreme difficulty encountered in breaking these emulsions. Distillation of the oil over caustic, does not give rise to emulsion difficulties but for some reason or other, as indicated above, the resulting distillates 20 have a bluish cast instead of the desired green cast.

It has been discovered that naphthenic acids can be removed from this oil by treatment with alkali in the presence of a diluent, such as propane, without encountering particular difficulty with respect to the formation of emulsions. By carrying out the treatment under certain specified conditions, as will be explained more fully, it is possible to substantially avoid the formation 25 of emulsions which are difficult to break. Propane deasphalting, coupled with treatment with the alkali, produces a product of superior characteristics and also avoids the necessity for subjecting the resulting oil stock to treatment with 30 sulphuric or other inorganic acids as practiced in the prior art.

It is advantageous to employ the alkaline treatment of this invention in conjunction with deasphalting of the oil with a solvent such as 40 propane, because the propane used in the deasphalting step serves as a diluent in the alkali treating step, thus acting as a common diluent in both steps. It is possible that the propane facilitates the retention of the desirable color-forming 45 constituents in the oil during the treatment with alkali, thus preventing their removal in the saponified material, as is the case when distilling the oil over caustic, as explained above.

In order to illustrate the invention further, 50 reference will now be made to the accompanying drawing:

A residual naphthene base lubricating oil stock, obtained by distilling the lighter fractions from a Gulf Coastal crude, is conducted from a source 55

not indicated to a mixer 1. Propane, conducted from a source not indicated, is introduced to the mixer 1 wherein it is mixed with the lubricating oil stock in the proportion of about 8 to 12 parts 5 of propane to 1 part by volume of stock. The resulting mixture is conducted to a separator 2 wherein it is subjected to settling at a temperature around 70° F. to 180° F. in order to precipitate asphaltic constituents. The thus deasphalted solution is advantageously conducted to a second separator 3 for the precipitation of further asphaltic constituents of a resinous nature and which is effected by maintaining the mixture at a somewhat higher temperature, for example, 10 around 130° F. to 200° F. If desired, an additional quantity of propane may be mixed with the charge to the separator 3.

The completely deasphalted solution is now drawn off from the separator 3 and introduced to 20 the lower portion of a treating tower 4. This tower may be provided with suitable packing material. Advantageously, the packing may consist of several perforated cones 5 located in the lower portion of the tower. These cones are for the purpose of effecting contact and mixing between the entering propane-oil mixture and the alkali.

Above the cones, and extending into the upper portion of the tower, grids 6 may be provided, advantageously consisting of wire screening.

30 Alkali, consisting of caustic soda dissolved in water, is introduced to the upper portion of the tower as indicated. In starting up the tower it is advantageous to fill it first with the mixture of propane and oil and then commence charging the caustic soda solution, allowing the level of the caustic solution to build up slowly to a desired level a short distance above the cones 5 and corresponding to the point indicated by liquid level indicator 7. The liquid level is maintained at this 35 point during the continuous operation of the tower by drawing off the spent caustic continuously from the bottom of the tower as indicated. In other words the interface level between the caustic layer and the oil layer is maintained relatively low in the tower. Sufficient pressure must be maintained on the system so as to maintain the diluent in a liquefied condition during the caustic treatment as well as during the preceding deasphalting treatment.

40 The treated oil solution is continuously withdrawn from the top of the tower through a pipe 8. Through the pipe 8 the treated solution is conducted to a settling tank 9 where any aqueous carry over may be separated from the oil and drawn off. The settled mixture is then conducted to a stripper 10 wherein the propane is 45 stripped from the oil.

Where it is desired to recover the naphthenic acids from the mixture being drawn off from the bottom of the tower 4, this can be accomplished in the usual fashion by treatment with an inorganic acid so as to liberate the naphthenic acids.

46 The mixture of spent caustic drawn off from the bottom of the tower 4 may, if desired, be introduced to a washing tower 11, provided with suitable packing material, and wherein it is washed with an additional quantity of the liquefied hydrocarbon solvent. The spent caustic solution is introduced to the upper portion of the tower, while a solvent, such as propane, is introduced to the lower portion of the tower. The washing is thus effected on the countercurrent principle for the purpose of removing from the spent caustic oil which may be associated therewith.

The washed caustic material is drawn off from the bottom of the tower 11 while the solution of oil and propane is removed from the top of the tower and advantageously conducted to a washing tower 12, somewhat similar to tower 11, but in which the washing agent comprises water. The water and sludge is withdrawn from the bottom of the tower 12, while the washed solution of oil and propane is removed from the top of the tower and conducted to a stripper still to separate the solvent from the oil.

5 It is advantageous to employ a weak caustic soda solution in the tower 4 so as to prevent salting out of the naphthenic acid soaps during treatment within the counter-current tower. The caustic soda solution employed advantageously consists of around 0.2% to 0.5% by weight of caustic soda. It is advantageous to use it in substantial excess—that is, from 25% to 200% by volume in excess of the amount required to neutralize the organic acidity contained in the oil undergoing treatment. While more concentrated caustic solutions may be used as shown in the subsequent example, it is usually preferable to employ it in the less concentrated form.

20 While caustic soda has been specifically mentioned, it is contemplated that other alkaline reagents may be employed, such as ammonium hydroxide or potassium hydroxide.

25 While in the foregoing description the alkali treatment follows the deasphalting step, it is contemplated that instead it may precede deasphalting. If desired, the diluted oil may be subjected to alkali treatment subsequent to the initial deasphalting step and prior to the final deasphalting step for removal of resinous constituents.

30 The following results were obtained in treating a residual lubricating oil fraction having a viscosity of 270 Saybolt Universal seconds at 210° F. and derived from Manvel crude. Two runs were made. In the first run the residuum was subjected to deasphalting without a subsequent caustic treatment, while in the second run it was subjected to both deasphalting and caustic treatment. The residuum was diluted with propane in the proportion of ten parts of propane to one part of residuum and asphalt precipitated therefrom at a temperature of 163° F. The remaining solution was then treated with an additional quantity of propane, about three or four volumes, to remove the resinous constituents at a temperature of around 165° F.

35 The same procedure was followed in the run in which caustic treatment was applied, the caustic treatment being applied before recipitation of the resinous constituents. A relatively strong caustic solution was used in this instance, consisting of 25% by weight of caustic. The solution was used in the proportion of about 2.2 volumes to 1 volume of residuum.

	Residuum	Treated oil		65
		1 Deasphalts without caustic treatment	2 Deasphalts with caustic treatment	
Gravity, °A. P. I.	19.0	21.9	22.0	70
Color, Tag Rob.		1/2	1/2	
Carbon residue, percent	3.95	1.58	1.61	
Neutralization number	0.45	0.28	0.04	
Yield:				
Basis charge, percent		66.5	67.8	75

The oil obtained by deasphalting and caustic treatment possessed the desired green cast; also, as indicated, the treatment with caustic effectively reduced the neutralization number.

5 In another example a Manvel residuum having the following tests:

Gravity, °A. P. I.	19.5
Flash	500
Fire	580
10 Vis./210	205
Color, Tag Rob.	
Pour °F	15
Carbon residue percent	3.44
15 Neutralization number	0.90

was subjected to treatment in accordance with our invention. This involved first subjecting the residuum to deasphalting and deresinating by treatment with a volume of propane equal to twelve times the volume of the residuum. This was carried out in a countercurrent treating tower, the temperature at the top of the tower being 164° F. and the temperature at the bottom being 163° F. In the course of this treatment 20 the asphaltic and resinous materials were precipitated and removed simultaneously.

The propane solution of deasphalting and deresinated oil was drawn off continuously from the top of the tower and then subjected to continuous treatment with approximately 77% by volume on the basis of charge oil of a 0.26% by weight aqueous solution of caustic soda, the extraction with caustic soda solution being carried out at a temperature of 155° F. The caustic treated oil was then separated from the propane. It had the desired green cast and on testing was found to have the following tests:

Gravity, °A. P. I.	20.8
Flash	500
40 Fire	580
Vis./210	157
Color, Tag Rob	1/8
Pour °F	30
Carbon residue, percent	1.84
45 Neutralization number	0.07

Obviously, many modifications and variations of the invention, as hereinbefore set forth, may be made without departing from the spirit and 50 scope thereof, and therefore only such limitations should be imposed as are indicated in the appended claims.

We claim:

1. The method of preparing lubricating oil 55 suitable as cylinder stock, substantially free from asphaltic and acidic constituents and having a desirable green cast, from reduced naphthene base crude comprising diluting the oil with a liquefied normally gaseous petroleum hydrocarbon solvent, deasphalting the oil in the presence of said liquefied solvent and treating the oil without intervening treatment with inorganic acid with a large excess of dilute caustic soda solution in the presence of said liquefied solvent 60 to remove the acidic constituents of the oil without substantially affecting adversely the constituents of the oil imparting the desired green cast.

2. The method of preparing lubricating oil 70 suitable as cylinder stock, substantially free from asphaltic and acidic constituents and having a desirable green cast, from reduced naphthene base crude comprising diluting the oil with a liquefied normally gaseous petroleum hydrocarbon solvent, deasphalting the oil in the presence of said liquefied solvent and treating the oil with

about 0.2% to 0.5% caustic soda solution in amount about 25 to 200% by volume in excess of that required to neutralize the organic acidity and in the presence of said liquefied solvent to remove the acidic constituents of the oil without 5 adversely affecting the constituents of the oil imparting the desired green cast.

3. In the countercurrent treatment of lubricating oil stock derived from naphthene base crude petroleum with caustic soda solution to remove 10 organic acidity, the steps comprising diluting the oil with a liquefied normally gaseous petroleum hydrocarbon solvent, continuously introducing the diluted mixture near the bottom of a packed tower filled substantially with dilute mixture 15 maintained under pressure sufficient to maintain the diluent liquefied, continuously introducing the caustic soda solution near the top of said tower and maintaining the interface between the caustic soda solution and the oil intermediate the 20 points of oil and caustic introduction such that the oil is forced to rise through a substantial body of caustic solution within the lower portion of the tower.

4. In the continuous method of treating lubricating oil stock with a hydroxide solution selected from the hydroxides of the alkali group consisting of sodium, potassium and ammonium, the steps comprising diluting the oil with a liquefied 25 normally gaseous petroleum hydrocarbon, charging the dilute oil near the bottom of a packed tower, charging the reagent near the top of said tower, maintaining the diluted oil under pressure sufficient to maintain the diluent liquefied, maintaining the interface level between the reagent 30 and the oil within the tower at a point intermediate the points of oil and reagent introduction to the tower, thereby causing the oil to flow through a substantial body of reagent within the lower portion of the tower, withdrawing used reagent 40 and sludge from the bottom of the tower, and withdrawing the treated dilute oil from the top of the tower.

5. The method of preparing lubricating oil, suitable as cylinder stock, substantially free of asphaltic and acidic constituents and having a desirable green cast, from reduced naphthene base crude, comprising mixing the oil with a liquefied normally gaseous petroleum hydrocarbon solvent in proportion sufficient to precipitate 50 substantially all the asphalt, removing the asphalt in the presence of the liquefied solvent and treating the deasphalting oil, without subjecting it to an intervening treatment with inorganic acid and while still mixed with the liquefied solvent, with a large excess of a dilute solution of a hydroxide selected from the hydroxides of the alkali group consisting of sodium, potassium and ammonium to remove the organic acidic constituents of the oil without substantially affecting adversely the constituents imparting said green cast to the oil. 55

6. The method according to claim 5 in which the liquefied hydrocarbon comprises mainly propane.

7. The method of preparing lubricating oil, suitable as cylinder stock, substantially free from asphaltic and acidic constituents and having a desirable green cast, from reduced naphthene base crude, comprising mixing the oil with a liquefied normally gaseous petroleum hydrocarbon, deasphalting the oil in the presence of said liquefied solvent and treating the oil, without an intervening treatment with inorganic acid, with a large excess of dilute caustic alkali solution in the presence of said liquefied solvent to remove the 70 75

organic acidic constituents of the oil without substantially affecting adversely the constituents imparting the desired green cast.

8. The method according to claim 5 in which the resulting deacidified oil is treated with further liquefied solvent to remove resinous constituents.

9. In the method of preparing naphthene base cylinder stock of desirable green cast from reduced naphthene base crude and not requiring treatment with inorganic acid, the combination of steps which comprises diluting the residuum with a liquefied normally gaseous petroleum hydrocarbon capable of precipitating asphaltic constituents therefrom, subjecting the diluted mixture to settling to remove asphaltic constituents, treating the diluted mixture with a dilute hydroxide solution selected from the hydroxides of the alkali group consisting of sodium, potassium and ammonium, said hydroxide solution being in large excess of the amount required to neutralize the organic acidity of the oil undergoing treatment, such that organic acidic constituents of the oil are removed without substantially affecting adversely the constituents imparting said green cast to the oil, and maintaining the dilute mixture during said deasphalting and alkali treating steps under pressure sufficient to maintain the diluent liquefied.

10. In the method of preparing naphthene base cylinder stock of desirable green cast from reduced naphthene base crude, the combination of steps which comprises diluting the reduced crude with a liquefied normally gaseous petroleum hy-

drocarbon, removing asphaltic constituents from the reduced crude in the presence of the liquefied diluent, and treating the reduced crude in the presence of the liquefied diluent with a dilute hydroxide solution selected from the hydroxides of the alkali group consisting of sodium, potassium and ammonium, said solution amounting to about 25 to 200% by volume in excess of that required to neutralize the organic acidity of the oil and having an alkalinity approximately equivalent to a caustic soda solution containing around 0.2 to 0.5% by weight of caustic soda.

11. The method of preparing lubricating oil, suitable as cylinder stock, substantially free from asphaltic and acidic constituents and having a desirable green cast, from reduced naphthene base crude, comprising mixing the oil with a liquefied normally gaseous petroleum hydrocarbon solvent, maintaining the diluted mixture under pressure sufficient to maintain the diluent liquefied, de-asphalting the mixture of oil and liquefied diluent, and treating the dasphalting mixture of oil and liquefied diluent with a caustic alkali solution amounting to about 25 to 200% by volume in excess of that required to neutralize the organic acidity of the oil, said solution having a concentration of around 0.2 to 0.5% by weight of caustic soda and such that organic acidic constituents of the oil are removed without substantially affecting adversely the constituents imparting said green cast to the oil.
